The ornamental design for a biometric scanning aperture for a computer input device, as shown and described.

DESCRIPTION

FIG. 1 is a side elevation view of a biometric scanning aperture for a computer input device;

FIG. 2 is a bottom perspective view of the biometric scanning aperture for a computer input device of FIG. 1;

FIG. 3 is a top perspective view of the biometric scanning aperture for a computer input device of FIG. 1;

FIG. 4 is a front perspective view of the biometric scanning aperture for a computer input device of FIG. 1;

FIG. 5 is a rear perspective view of the biometric scanning aperture for a computer input device of FIG. 1; and,

FIG. 6 is a bottom view of the biometric scanning aperture for a computer input device of FIG. 1.

The broken line drawing in all views of a computer input device is for illustrative purposes only and forms no part of the claimed design.
